CLAIM

The ornamental design for a tape measure device, as shown and described.

DESCRIPTION

FIG. 1 is a top, front and left side perspective of a tape measure device, showing our new design;

FIG. 2 is a top, front and right side perspective of the tape measure device shown in alternate environment with tape measure extended;

FIG. 3 is a front view of the tape measure of FIG. 1;

FIG. 4 is a back view of the tape measure of FIG. 1;

FIG. 5 is a top view of the tape measure of FIG. 1;

FIG. 6 is a bottom view of the tape measure of FIG. 1; FIG. 7 is a front end view of the tape measure of FIG. 1; and, FIG. 8 is a back end view of the tape measure of FIG. 1. The characteristic feature of the design resides in the overall appearance of the tape measure device.

Broken lines on the tape measure device in FIGS. 1, 3-4 and 6 depict an element that is not part of the subject device. The Broken lines in FIG. 2 depict a tape measure in alternate extended environment, the broken lines do not form part of the claimed design.
